UNITED STATES PATENT OFFICE.

CHARLES BILLINGTON AND RALPH F. GIBBS, OF ATTLEBORO, MASSACHUSETTS, AS-SIGNORS TO THE O. M. DRAPER CO., OF NORTH ATTLEBORO, MASSACHUSETTS, A CORPORATION OF RHODE ISLAND.

JOINT FOR BRACELETS.

1,107,132.

Specification of Letters Patent. Patented Aug. 11, 1914.

Application filed May 27, 1913. Serial No. 770,102.

To all whom it may concern:

Be it known that we, CHARLES BILLINGTON and RALPH FENNO GIBBS, citizens of the United States, and both residing at Attleboro, in the county of Bristol and State of Massachusetts, have invented a new and useful Improvement in Joints for Bracelets, of which the following is a specification.

Our invention consists in a two-part joint 10 for bracelets, having the parts so arranged and interlocked as to permit the bracelet to be opened for a certain distance to allow it to be passed over the hand of the wearer, and closed on the arm.

15 The object of our invention is to produce a cheaply made movable joint, without the employment of pivot pins and the like, which by wear are apt to drop out and be lost.

20 Figure 1 is an elevation of a bracelet, with the lower part in section to show the joint. Fig. 2 is a perspective view of the top of the joint with the joint closed. Fig. 3 is a top view of the joint with the joint open. 25 Fig. 4 is a longitudinal section on line IV—IV of Fig. 6. Fig. 5 is a longitudinal section on line V—V of Fig. 3. Fig. 6 is a bottom view of the joint with the joint closed. Fig. 7 is a transverse section on the

30 line VII—VII of Fig. 5.

The joint is formed of two members A and B. These members each consist of two parts, *i. e.*, the parts C—C¹, through which the members are attached, by soldering or 35 otherwise, to the interior of the bracelet D, and the parts E—E¹, which are interlocked to form a movable sliding joint. The part E has formed in it a slot F adapted to receive an ear G on the end of the part E¹, 40 which ear when the bracelet is opened, contacts with the end wall H of slot F to limit the movement of members A and B of the joint relative to each other.

The part E is provided with ears I which 45 are turned over the part E¹ and which serve to hold the parts E and E¹ in operative rela-

tion. The part E has also formed in it a slot J in which is located a correspondingly shaped elevation K on part E¹. The parts C—C¹ are shown convex on one side and 50 concave on the other in the direction of their length, and the parts E—E¹ convex on one side and concave on the other in the transverse direction of the joint.

We wish it understood that we do not 55 limit ourselves to the particular shape of the members of the joint, as modifications will be obvious to those skilled in the art.

Having thus described our invention, we claim:

1. In a bracelet hinge, duplicate body portions each provided with a curved interlocking portion, one of said interlocking portions being provided with a longitudinal slot and a groove adjacent said slot, a rib on 60 the other portion adapted to enter said groove, an ear on said portion located within said slot, and laterally disposed ears on the first mentioned interlocking portion adapted to be bent to hold the two portions 65 in engagement.

2. In a bracelet hinge, an attaching member, a curved member extending therefrom, said member being provided with a longitudinal slot and a groove, laterally extending 75 ears carried by said member and adapted to be bent into clamping position, a complementary attaching member, a curved member extending therefrom and slidably engaged between the aforesaid curved member 80 and the ears, an ear on said last mentioned member adapted to enter the slot, and a longitudinal rib on said curved member adapted to enter the groove.

In testimony whereof, we affix our signatures, in the presence of two witnesses.

CHARLES BILLINGTON.
RALPH F. GIBBS.
